UNITED STATES PATENT OFFICE

FRED McMANIS, OF HOUSTON, TEXAS, ASSIGNOR TO W-K-M COMPANY, OF HOUSTON, TEXAS, A CORPORATION OF TEXAS

TRACTOR ATTACHMENT FOR PIPE CLEANERS

Application filed May 6, 1927. Serial No. 189,283.

My invention relates to an attachment for tractors whereby a pipe cleaner may be supported and operated in the field by power furnished either from the tractor itself or 5 from some other and separate source of power.

In cleaning the outside of larger sizes of pipes, such as are employed in pipe lines, for the transportation of oil, gas or other fluid, 10 it is necessary to support and operate the cleaner along the pipe in the ditch in which the pipe is laid. Although the pipe may sometimes be elevated upon skids for cleaning, it is often impossible to lift the pipe from its 15 position in the ditch, due to the fact that the pipe has become rusted and corroded until it is so weak, particularly at the joints, that it cannot be moved without serious danger of breakage and consequent waste of oil or other 20 fluid carried by the pipe. The pipe cleaner must be supported and moved along the pipe while the cleaner is operated to clear the pipe of rust and scale, so that a protecting coating of paint or composition may be applied thereto.

Heretofore, cleaners of this nature have been supported for operation by the pipe itself, the pipe furnishing a track upon which the cleaner is supported and propelled. This 30 system is subject to some objectionable features. It sometimes is dangerous to the pipe to rest the full weight of the cleaner upon the pipe; for the motor and frame, as well as the cleaning elements all must be supported 35 upon the pipe in such case and the weight of such an apparatus is necessarily great. Furthermore, the actuating and supporting mechanism must be located in the ditch where 40 they cannot be conveniently reached by the operator.

It is an object of my invention to provide an attachment for tractors whereby the cleaner may be supported and moved along the pipe 45 while it is in the ditch or when elevated upon skids, said tractor also furnishing the necessary power to rotate the cleaner.

It is desired to support and move the cleaner along the pipe in such manner that no 50 appreciable weight will be exerted upon the

pipe and also to assure that the cleaner will act uniformly upon all sides of the pipe.

I aim to make the cleaner readily adjustable to different levels while it is being operated and to move the cleaner at any desired 55 speed along the pipe.

Referring to the drawings herewith, Fig. 1 is a side elevation of a tractor equipped with my attachment, certain parts being broken away for greater clearness. Fig. 2 is a rear 60 elevation of the apparatus. Fig. 3 is a view of the cleaner in end view with the parts in open arrangement. Fig. 4 is an end view of the cleaner in closed operative arrangement; and Fig. 5 is a broken rear view of a modified form of attachment. Like numerals of reference are employed to designate like parts in all the views.

The tractor with which my attachment may be used may be of any preferred make. I 70 have shown the attachment applied to a make of tractor now extensively used. It is of the caterpillar type having rear wheels 1 and front wheels 2 connected by the tractor chain 3. Its frame or chassis is of the usual construction and furnishes a support for my attachment which is constructed to fit thereon.

It is contemplated that the tractor will be driven along the side of the ditch shown at 4 and that the cleaner, indicated generally 80 at A, will be suspended on a boom B mounted upon the tractor.

The boom B comprises a body 5, preferably of tubular construction, and mounted in an inclined position, as shown in Fig. 2, so that 85 the upper end thereof will project from the side of the tractor to a position immediately over the pipe. This boom is provided with supporting legs 6 and 7 which are secured to the frame of the tractor in any convenient 90 position so as to firmly support the boom in the position stated. The boom is reinforced on its upper side by a strut 8 and at the lower end of said strut a plate 9 is placed which furnishes a support for disc-shaped weights 95 10 of any desired diameter and weight sufficient to counterbalance the ordinary load to be carried by the upper end of the boom.

The forward end of the boom has a hooked end 11 to which is secured a yoke or frame 100

12 furnishing a mounting for a sheave having two pulleys 13 therein. Spaced inwardly from the upper end of the boom is a supporting yoke 14 upon which is mounted the pulley 15, over which a separate cable 16 may pass. The cable 17 is wound upon a reel or spool 18 toward the lower side of the boom, said reel being rotatable through a crank arm 19 and having thereon a ratchet 60 engaging with a pawl 61 upon the frame of the boom to hold the reel in any adjusted position. The cable 17 passes upwardly over one of the pulleys 13 and the two cables 16 and 17 depend from the upper end of the boom and are attached to a latching member 20 of the C-hook type commonly used in oil well operations.

Mounted upon the supporting legs 7 of the boom is an arcuate rod 21 curved outwardly 20 away from the tractor and furnishing means whereby the cleaner may be supported when out of use. A rod 22 extending from the boom downwardly to the member 21 serves to strengthen said member and acts as a 25 guide for weights 23 secured to the inner end of the cable 16 and acting to counterbalance the weight of the cleaner frame A on said cable.

The cleaner shown in the drawings may be 30 understood as representing any desirable form of cleaner. The exact construction of this member forms the subject matter of a separate application and is no part of the present invention. The construction of the 35 cleaner is shown, however, in the drawings. It comprises a cylindrical frame work 24 which is made in two parts pivoted at 25 and having a latch on the opposite side 26. Upon this frame work are a series of hinged doors 40 27 adapted to be swung outwardly away from the frame into the position shown in Fig. 3 when access is to be obtained thereto or when the cleaner is to be passed over a collar or other projection upon the pipe. Upon each 45 of these doors is mounted a series of cleaning elements including brushes 28 and cleaning rollers 29. These cleaning elements are held resiliently and inwardly toward the pipe and are adapted to chip and brush the rust and 50 corrosion from the pipe surface as the frame work is rotated.

This frame work as shown in Fig. 1 is mounted centrally within a supporting frame 30. This support engages the frame work of 55 the cleaner intermediate the ends thereof and a housing is formed about said frame, said housing extending upwardly away from the cleaner so as to house a sprocket chain 31 passing over a sprocket wheel 32 at the upper 60 end of the housing and extending downwardly about a sprocket wheel formed upon the frame work of the cleaner in an obvious manner.

The sprocket wheel 32 is formed upon a 65 short shaft 33 mounted within the housing

and supported thereby at each end. The said shaft projects through one side of the housing and has thereon a beveled gear 34 which is adapted to mesh with a similar gear or pinion 35 upon the end of the shaft 36. 70 The upper end of the housing has a yoke or clevis 37 thereon to which the hook 20 may be engaged to support the said housing.

The shaft 36 has a universal joint 38 therein of any preferred construction to allow the 75 changes in position of the housing relative to said shaft. The shaft is also made extensible longitudinally by having a sleeve on the forward end of said shaft telescoping over a rod 39 on the inner end of said shaft, there 80 being a driving connection between said rod and sleeve.

The ordinary tractor has a power take-off including a shaft extending laterally from the transmission housing of the tractor. As 85 this take-off shaft is on the right-hand side of the tractor as it is viewed from the rear, I have connected said take-off shaft with a line shaft 40 at the rear end of the tractor frame. A sprocket wheel 41 thereon is connected 90 with a similar wheel on the take-off shaft, thereby serving to rotate the shaft 40. Said shaft 40 extends across the rear end of the tractor and is operatively connected at its other end to a stub shaft 42 mounted in the 95 frame of the car and having thereon a beveled gear 43 which in turn meshes with a similar gear 44 upon the shaft 45, also mounted in the frame of the car and extending forwardly to approximately midway between the ends of the tractor where it is connected through beveled gears with the shaft 39, previously referred to. A second universal joint 100 46 may be employed in connection with the shaft 39 for greater flexibility in the operation of the shaft.

In order to move the cleaner frame A and the cleaner longitudinally of the pipe in performing the cleaning operation, I connect the frame A with arms 47 and 48, projecting 110 from the frame of the tractor at points spaced on the forward and rear sides of the said frame A. These arms project to a point below the shaft 33 on the cleaner frame and are secured to hooks 48 on the forward and rear sides thereof by means of links 49 and tension springs 50. In this manner, the traction effect upon the cleaner frame may be exerted from the forward or rearward side thereof to act resiliently on the frame 115 through the effect of the springs 50 so that there will be no abrupt or violent pull upon the said frame.

In the operation of the device, the tractor will be driven along the side of the ditch in 125 which the pipe is laid and the pipe will be elevated gradually at spaced points to allow the cleaner frame to be engaged about the pipe. This will be done in an obvious manner, as seen from Figs. 2 and 3. The opera- 130

tion of the tractor engine may be communicated at different speeds from the power take-off through the connections shown to the shafts 36 and 33 and the sprocket chain 31 5 may be actuated to rotate the cleaner frame work within the frame 30. As the pipe is thus gradually cleaned, the tractor will be moved along the side of the ditch and parallel therewith to guide the cleaner along the 10 pipe. Any inequalities in the ground and the difference in the levels of the two wheels of the tractor may be accommodated by a raising and lowering of the frame A relative to the tractor. The springs 50 will allow the 15 frame to be raised and lowered relative to the tractor frame without interfering with the moving of the cleaning frame along the pipe. Ordinarily the weights 23 will exactly balance the weight of the frame A so that any 20 variation in the level of the pipe relative to the tractor chassis will be automatically compensated through the said weights and to allow this automatic adjustment. The reel 18 will be released by withdrawing the pawl 25 61 from connection therewith so that the weight of the frame will be entirely under the control of the balancing weights 23. The universal joints within the shaft 36 will allow the operation of the cleaner without interfering 30 in any way with the rotation of the said shaft.

When the cleaner is to be detached from the pipe and moved away from the ditch, the cable 17 will be reeled up so as to raise the 35 frame work free of the ditch and to the level of the rod 21. A chain or cable may be then used to anchor the cleaner frame in a position resting upon the bar 21 where it may be supported while the device is being moved from 40 place to place. To accommodate this movement, the links 49 on the chassis frame may be easily detached from the cleaner frame in an obvious manner.

In some cases, the pipe is in such condition 45 that it may be elevated from the ditch and placed on skids for cleaning. Fig. 5 illustrates the use of my device in such a connection. The skids 52 are extended across the ditch and the pipe, indicated at 53, is supported thereon. The skids may be moved 50 from place to place along the pipe as the cleaner is operated thereon. Under such conditions, the arms 47' upon the tractor frame are extended upwardly at an angle relative 55 to the frame so as to engage the cleaner frame A in its elevated position. The universal joints 38 and 46 allow the operation of the cleaner in its raised position without interfering at all with the efficient action of the driving 60 connection. The operation of the device and the connection thereof in other details will be practically identical with that shown in the usual form of the device. It is possible, therefore, with very little change in the construction of the attachment to provide for the 65

operation of the cleaner either within the ditch or upon pipe supported at the level of the tractor.

The advantages of this construction lie in the fact that the pipe may be cleaned without the resting of any weight thereon. The cleaner may be moved along the pipe and also supported in proper position thereon by the tractor itself, so that it will move along the pipe with no danger to the pipe itself. The 70 positioning of the cleaner upon the pipe will be practically automatic through the balancing of the weights 23, and the power already present in the engine of the tractor may be employed in operating the cleaner, as described. 75

While I have shown and described the cleaner as being operated from the tractor, it is to be understood that I do not wish to be confined to this particular source of power as any individual power unit may be employed as desired, depending upon the conditions to be overcome in the field. 80

Having thus described my invention, what I claim as new and desire to protect by Letters Patent is:

1. A pipe cleaner attachment for tractors including a boom, a support therefor on said tractor, a cable on said boom, a frame suspended on said cable, a pipe cleaner supported in said frame, a shaft at the upper end of said frame, means to rotate said cleaner from said shaft, a power take-off from said tractor, and operative connections between said power take-off and said shaft. 95

2. A pipe cleaner attachment for tractors including a boom, a support therefor on said tractor, a cable on said boom, a frame suspended on said cable, a pipe cleaner supported in said frame, a shaft at the upper end of said frame, means to rotate said cleaner from said shaft, a power take-off from said tractor, operative connections between said power take-off and said shaft, and means on said tractor connected with said frame to move said frame and cleaner with said tractor along said pipe. 100

3. A pipe cleaner attachment for tractors including a boom, a support therefor on said tractor, a cable on said boom, a frame suspended on said cable, a pipe cleaner supported in said frame, a shaft at the upper end of said frame, means to rotate said cleaner from said shaft, a power take-off from said tractor, operative connections between said power take-off and said shaft, lateral arms on said tractor and means connecting said arms to said frame for the purpose described. 115

4. A pipe cleaner attachment for tractors including a boom, a support therefor on said tractor, a cable on said boom, a frame suspended on said cable, a pipe cleaner supported in said frame, a shaft at the upper end of said frame, means to rotate said cleaner from said shaft, a power take-off from said tractor, operative connections between said power take-off 120

- and said shaft, and resilient means connecting said frame with said tractor, whereby said frame and cleaner may be moved along the pipe.
5. A cleaner for the outside of pipe lines including a frame surrounding the pipe, a cleaning element in said frame adapted to engage the outer surface of the pipe, and means independent of the pipe to support said frame and cleaning element while said element is operated.
6. A cleaner for the outside of pipe lines including a frame, a cleaning element in said frame adapted to engage the outer surface of the pipe, means including a vehicle adapted to travel at the side of the pipe to support said frame and cleaning element while said element is operated, and means to move said cleaning element along said pipe line.
7. A cleaner for the outside of pipe lines including a frame shaped to surround said pipe, a cleaning element in said frame adapted to engage the outer surface of the pipe, means independent of the pipe being cleaned to support said frame and cleaning element while said element is operated, and means connected with said first means to impart motion to said cleaning element.
8. A cleaner for the outside of pipe lines including a frame, a cleaning element in said frame adapted to engage the outer surface of the pipe, a portable support including a tractor adapted to travel on the ground adjacent said pipe, vertically adjustable means thereon to sustain the weight of said cleaning element and means on said support to rotate said element.
9. A cleaner for the outside of pipe including a frame, a rotatable cleaning element in said frame, a portably mounted support independent of said pipe, a cable thereon connected with said frame, means on said cable to balance the weight of said frame, means to rotate said cleaning element, and additional means to move said cleaning element along said pipe.
10. A cleaner for the outside of pipe including a frame, a rotatable cleaning element in said frame, a portably mounted support independent of said pipe, a cable thereon connected with said frame, means to rotate said cleaning element, and additional means to move said cleaning element along said pipe.
11. A cleaner for the outside of pipe including a frame, a rotatable cleaning element in said frame, a portably mounted support independent of said pipe, a cable thereon connected with said frame, means to control said cable to raise and lower said frame as desired, means to rotate said cleaning element, and additional means to move said cleaning element along said pipe.
12. In a device of the character described, a frame, a pipe cleaning element therein, a tractor, a boom thereon, a cable on said boom connected with said frame to flexibly support said frame, means on said cable to balance the weight of said frame and cleaning element, and means to operate said cleaning element.
13. In a device of the character described, a frame, a pipe cleaning element therein, a tractor, a boom thereon, a cable on said boom connected with said frame to flexibly support said frame, means on said cable to balance the weight of said frame and cleaning element, means to raise and lower said frame, and a power connection between said tractor and said cleaning element, whereby said element may be operated.
14. In a device of the character described, a frame, a pipe cleaning element therein, a tractor, a boom thereon, a cable on said boom connected with said frame to flexibly support said frame, means on said cable to balance the weight of said frame and cleaning element, a power take-off on said tractor, a flexible shaft operatively connected therewith, and means on said frame for communicating rotative movement from said shaft to said cleaning element.
15. A cleaner for the outside of pipe lines including a frame, a cleaning element in said frame adapted to engage the outer surface of the pipe, means independent of the pipe to support said frame and cleaning element while said element is operated, means connected with said support to impart a rotating motion to said cleaning element, and means to move said support and said cleaning element along said pipe line.
16. In a device for cleaning a pipe in position along a ditch, comprising a frame fitting about said pipe, a pipe cleaning element in said frame, portable means adapted to travel along said ditch to support said frame, means to vary the height of said frame relative to said support, and means to operate said pipe cleaning element.
17. In a device for cleaning a pipe in position along a ditch, comprising a frame fitting about said pipe, a pipe cleaning element in said frame, portable means adapted to travel along said ditch to support said frame, and means to operate said pipe cleaning element while said frame and cleaner are travelling along said pipe.
- In testimony whereof I hereunto affix my signature this 2nd day of May, A. D. 1927.
- FRED McMANIS.
